(57) **CLAIM**

The ornamental design for a holder, as shown and described.

DESCRIPTION

FIG. 1 is a perspective view of a holder showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is a partial enlarged view of the dash-dot-dash circle 9 shown in FIG. 1; and,

FIG. 10 is a perspective view of the holder in environmental use with a hat shown in broken lines.

The evenly-spaced broken lines shown represent environmental subject matter and form no part of the claimed design. The dash-dot-dash broken lines shown represent the boundaries of the partial enlarged view and form no part of the claimed design.
